BENDING AND ANVIL DIE FOR TANGENT
BENDING APPARATUS

Lee B. Green, Lakewood, Ohio

Application December 28, 1946, Serial No. 718,955

4 Claims. (Cl. 153—46)

1

This invention relates to bending machines of the kind intended for use in bending flanged metal workpieces. More specifically, the invention relates to apparatus for bending workpieces of the type having a web portion and one or more continuous longitudinal flanges and with which the workpiece is bent to a curved or angular shape by bending the web portion out of its own plane and simultaneously bending the flange or flanges within their own planes.

The invention provides an improved bending machine or apparatus of this character in which novel means is employed for minimizing the tendency of the flange portions of the workpiece to wrinkle or buckle during the bending operation and for subsequently smoothing or ironing out such wrinkles or bulges as may actually occur in the flange portions of the workpiece.

Another object of the present invention is to provide bending apparatus of the character mentioned, having cooperating die members for accomplishing the bending operation and in which one of the die members has retaining and ironing means thereon adapted to cooperate with flange portions of the workpiece for decreasing the tendency to buckle and for subsequently smoothing out such wrinkles as may actually occur.

A further object is to provide improved bending apparatus of the kind embodying a group of cooperating die members including a pair of die members having a parting line therebetween and also having side flanges adapted to engage edge flanges of the workpiece and wherein the side flanges of one of the die members of the pair has extension portions adapted to span the parting line and to exert holding and smoothing actions on the flanges of the workpiece.

Still another object is to provide improved bending apparatus of the character mentioned, in which one of the die members is an anvil die and another is a bending die which is rockable around the anvil die for bending the flanged workpiece therearound and wherein the side flanges of the bending die have extension portions which exert a holding action on the flange portions of the workpiece during the working travel of the bending die and have a smoothing or ironing action on the flange portions during the return travel of the bending die.

The invention can be further briefly summarized as consisting in certain novel combinations and arrangements of parts hereinafter described and particularly set out in the claims hereof.

In the accompanying sheets of drawings

2

Fig. 1 is a side elevation of a bending machine embodying the present invention;

Fig. 2 is a partial top plan view of the machine;

Fig. 3 is a longitudinal sectional elevation taken 5 through the machine substantially as indicated by line 3—3 of Fig. 2;

Fig. 4 is a partial longitudinal sectional elevation similar to Fig. 3 but showing the position of the bending die at or near the end of its working 10 travel;

Fig. 5 is a partial vertical sectional view taken near the front end of the machine as indicated by line 5—5 of Fig. 3;

Fig. 6 is a partial vertical sectional view taken 15 on line 6—6 of Fig. 5 and showing the fulcrum mounting for the rocker plate;

Figs. 7 and 8 are perspective views showing a pair of the cooperating die members in detached 20 relation, and

Fig. 9 is a perspective view showing a workpiece after the bending operation thereon but prior to the smoothing or ironing operation on the edge flanges thereof.

As one embodiment of the present invention the 25 accompanying drawings show a bending machine or apparatus 10 for carrying out a bending operation on a flanged or channel-shaped metal workpiece such as the workpiece 11 shown in this instance. A bending machine of the type here 30 shown is more fully disclosed in earlier application Serial No. 571,979, filed January 9, 1945.

The machine 10 includes a frame having laterally spaced upright side walls 12 and an upright front wall 13 extending between such side walls 35 and having thereon a die support or bolster 14 which also extends laterally between the side walls 12 and carries a die member 15. The machine also includes a pivoted carrier 16 which is located between the side walls 12 and carries a second 40 die member 17. The carrier 16 comprises a pair of rearwardly extending arms 16a located adjacent the side walls 12 and having their rear ends pivoted on such side walls by means of the pivot pins 18. At its forward end the carrier 16 is 45 provided with a transverse beam 19 on which the die member 17 is mounted as by means of the T-slots 20 and bolts 21. The machine 10 also includes a wing 23 extending across the front of the machine and which is pivoted on the frame 50 for forward and upward swinging movement around the die member 17. The wing 23 carries a rocker plate 24 on which a third die member 25 is mounted.

The wing 23 is here shown as being a hollow 55 metal structure having a pair of arms 27 which

are pivoted on pivot pins 28 carried by the sides 12 of the frame. The wing contains a pressure roller 29 which acts on the flat undersurface of the rocker plate 24 and is urged thereagainst by compression springs 30. The rocker plate 24 is fulcrumed on the frame of the machine for the desired rocking movement around the die member 17 and for this purpose the sides 12 of the frame are provided with gear sectors 31 which are suitably mounted thereon in substantially concentric relation to the pivot pins 28. The rocker plate 24 has racks 32 mounted thereon adjacent its opposite side edges and which mesh with the gear sectors 31, as shown in Fig. 6.

Swinging of the wing 23 forwardly and upwardly causes a working stroke of the bending die member 25, as is explained more fully hereinafter, and swinging of the wing downwardly and rearwardly returns this die member to its initial position in which it is illustrated in Fig. 3. Suitable power means is employed for imparting these swinging movements to the wing 23, such as the pair of inclined hydraulic cylinders 34 shown in this instance and which are located adjacent the side walls 12 of the frame and have their lower rear ends pivotally connected with the frame by means of the brackets 35 and pivot pins 36. The cylinders 34 have piston rods 37 projecting therefrom and operably connected with the wing 23 by the pivot pins 38.

Suitable actuating means is also provided for the carrier 16 for producing a desired actuation of the die member 17. This actuating means is here shown as comprising an upright hydraulic cylinder 40 located between the side walls 12 and having its lower end pivotally mounted on the frame by means of the pivot pin 41. A piston rod 42 projecting from the upper end of the cylinder 40 is connected with a rockshaft 43 by means of the lever 44. A pair of laterally spaced levers 45 are carried by the rockshaft 43 and are connected with the arms 16a of the carrier 16 by means of the links 46.

Oil under pressure, or other suitable motive fluid, is supplied to the power cylinders 34 and 40 by a pump 48 which is driven by an electric motor 49 through the belt 50. A tank or reservoir 51 contains a suitable supply of such oil or motive fluid.

The workpiece 11 which is shown in this instance is an elongated sheet metal member having an intermediate web portion 11a and continuous longitudinal edge flanges 11b. The workpiece 11 is initially in the form of a straight channel-shaped length, as shown in Fig. 3, and during the bending operation performed thereon by the present apparatus the web portion 11a is bent out of its own plane to the curved shape shown in Fig. 9 and the edge flanges 11b are simultaneously bent within their own planes.

During this bending operation there is a tendency for the edge flanges 11b to become wrinkled or buckled at or adjacent the beginning of the curve being formed therein. The die members which will be presently described in greater detail exert a holding action on the flanges 11b tending to prevent the formation of such wrinkles or bulges and also act to iron or smooth out any such wrinkles or bulges as may actually occur. For the purpose of better describing the invention, the workpiece 11 is shown in Fig. 9 as having wrinkles or bulges 53 in the edge flanges 11b thereof but it will be understood of course that these wrinkles or bulges will not be present in

the completed workpiece because they will have been ironed or smoothed out by the die members.

The die member 15 of the above mentioned die group is a work-supporting and clamping member. The die member 17 is a work-clamping member and is actuated by the carrier 16 for co-operation with the die member 15 for clamping the workpiece 11 therebetween. The die member 17 is also an anvil member having a curved anvil portion 17a about which the workpiece 11 is bent. As mentioned above, the member 25 is a bending die which is rockable about the anvil die member 17.

The die member 15 is best illustrated in Fig. 7 and comprises a plate or body having a substantially flat intermediate portion 54 upon which the web portion 11a of the workpiece 11 is received and also having substantially parallel side flanges 55 on opposite sides of the flat portion 54. The die member 15 also has lateral projections or flanges 56 thereon enabling the same to be bolted or otherwise connected to the support or bolster 14 of the frame. The side flanges 55 overlyingly engage the outer side faces of the edge flanges 11b of the workpiece. These side flanges are preferably formed in part by integral projections of the body of the die member 15 and in part by wear strips 57 of an angular cross-sectional shape which are recessed into the body of this die member.

The die member 17 has a width transversely of the machine 10 such that it will snugly enter the channel recess of the workpiece 11 and has a substantially flat bottom face 59 for clamping engagement with the web portion 11a of the workpiece. This die member also has flat side faces 60 which are engaged by the inner faces of the edge flanges 11b of the workpiece and against which these flanges are held by the side flanges 55 of the die member 15. The anvil portion 17a of the die member 17 is located at the front thereof and has the desired shape or curvature to which the workpiece 11 is to be bent. This curved anvil surface usually conforms to an arc whose center of curvature lies on the axis about which the wing 23 is swung, that is to say, lies on the axis of the pivot pins 28.

The bending die member 25 is generally similar to the die member 15 and comprises a plate or body having a flat intermediate portion 62 and substantially parallel side flanges 63 located on opposite sides of such flat portion and spaced apart so as to lie in alignment with the side flanges 55 of the die member 15 when the bending die member is in its initial position as shown in Fig. 3. The bending die member 25 preferably has lateral flanges 64 thereon enabling the same to be bolted to the upper surface of the rocker plate 24 of the wing 23. The side flanges 63 of the bending die are preferably formed in part by integral portions of the body of this die member and in part by wear strips 65 of an angular cross-section and which are recessed into the body of this die member as shown in Fig. 8.

Although the side flanges of the die members 15 and 25 have been described above as being preferably formed in part by integral portions of the die bodies and in part by the wear strips 57 and 65, it should be understood that the wear strips could be omitted or, if desired, the side flanges could be formed by the wear strips alone.

When the wing 23 is in its lower position, as shown in Fig. 3, the bending die member 25 is in an initial position in which its flat surface 62 is horizontally aligned with the flat surface 54

of the die member 15 and these two flat surfaces form a support upon which the web portion 11a of the workpiece rests when the workpiece is inserted into the machine. At this time the adjacent edges 15a and 25a of the die members 15 and 25 are substantially in meeting relation and define therebetween a common parting line 66 across which the workpiece extends. The side flanges 63 of the bending die member 25 also overlap the flat side faces 60 of the anvil die 17 and hold the edge flanges 11b of the workpiece thereagainst. As shown in Fig. 3 the curved anvil portion 17a of the die member 17 overhangs the parting line 66.

An important feature of the die mechanism of the improved bending apparatus is the means by which the tendency for the edge flanges 11b to buckle or wrinkle is decreased and by which wrinkles or bulges 53 which may actually form in such edge flanges are smoothed or ironed out. This means comprises extension portions 68 formed on the side flanges 63, or preferably on the wear strips 55, of the bending die member 25 and which portions or projections overhang the edge 25a so as to span the parting line 66 when the bending die member is in its initial position. The side flanges 65 of the die member 15, or preferably the wear strips 57 thereof, have recesses 69 extending into the ends thereof from the edge 15a. The projections 68 of the bending die member 25 are preferably of a tapered or rounded form and the recesses 69 of the die member 15 are of a corresponding shape so that the projections will be snugly received therein.

To explain the operation of the improved bending apparatus let it be assumed that the bending die member 25 is in its initial position as shown in Fig. 3 and that the workpiece 11 has been inserted. The cylinder 40 is then actuated to cause the upper die member 17 to clamp the workpiece against the lower die member 15. The cylinders 34 are then actuated to swing the wing 23 forwardly and upwardly thereby causing the rocker plate 24 to rock on the gear sectors 31 and also causing the bending die member 25 to rock around the curved anvil portion 17a of the die member 17. Slippage of the bending die member 25 on the curved anvil portion is prevented during this rocking movement by the meshing of the racks 32 with the gear sectors 31. The rocking of the bending die member 25 around the anvil portion 17a bends the workpiece 11 around the latter and the working stroke or travel of the bending die member continues until this member reaches the position shown in Fig. 4. During this bending operation the web portion 11a is bent out of its own plane and the edge flanges 11b are bent within their own planes.

The rocking movement of the bending die member 25 also causes the edge 25a thereof to move away from the adjacent edge 15a of the die member 15 and since this leaves portions of the edge flanges 11b of the workpiece exposed at or adjacent the parting line 66, the wrinkles or bulges 53 may occur in the edge flanges at this point. As the edge 25a of the bending die member 25 moves away from the adjacent edge 15a of the die member 15 the extension portions 68 of the side flanges of the bending die member are withdrawn from the recesses 69 of the die member 15, but since these extension portions overhang the edge 25a they will maintain the edge flanges 11b of the workpiece covered during a portion of such separating movement and will thus materially reduce the tendency for

wrinkles or bulges to be formed in the edge flanges.

When the working stroke of the bending die member 25 has been completed the cylinders 34 are actuated to swing the wing 23 back to its lowered position as shown in Fig. 3. This downward swinging of the wing causes a return movement of the bending die member 25 to its initial position and during this return movement the projections 68 accomplish an ironing action on the wrinkles 53 and cause the latter to be smoothed back into the planes of the edge flanges 11b. During this ironing action the projections 68 sweep over the wrinkles 53 by moving thereacross in a direction from the web portion 11a toward the free edges of the flanges 11b. This causes the wrinkles 53 to be flattened back into the planes of the edge flanges and during the accomplishment of this function the projections 68 re-engage in the recesses 69 of the die member 15 as the bending die member 25 assumes its initial position.

From the foregoing description and the accompanying drawings it will now be readily understood that the improved bending apparatus herein disclosed is adapted to accomplish a desired bending operation on a flanged or channel-shaped workpiece and that the cooperating die members thereof tend to prevent wrinkling or buckling of the flange or flanges of the workpiece and also act to produce a smoothing or ironing action on the flange or flanges for smoothing out wrinkles or bulges which may have occurred therein during the bending operation. Since any wrinkles or bulges which may occur in the flange or flanges of the workpiece will thus be automatically smoothed out during the return movement of the bending die member it will be seen that finished workpieces of a desired smooth and uniform character will be produced and it will not be necessary to subject them to further machine or manual operations for working bulges or wrinkles out of the flange or flanges thereof.

Although the improved bending apparatus has been illustrated and described herein in some detail it will be understood of course that the invention is not to be regarded as being correspondingly limited but includes all changes and modifications coming within the scope of the claims hereof:

Having thus described my invention, I claim:

1. In bending apparatus of the character described, a pair of die members having adjacent edges defining a parting line and each die member having a pair of substantially parallel side flanges thereon one die member of said pair being a holding die member and the other being a bending die member, and an anvil die member adapted to cooperate with said holding die member for holding therebetween a metal workpiece having a web portion and longitudinal edge flanges, said anvil die member having a curved anvil portion and said bending die member being rockable about said curved portion for bending the web portion of the workpiece out of its own plane and around said anvil portion and simultaneously bending said edge flanges within their own planes, the side flanges of one die member of said pair having recesses extending thereinto from said parting line and the side flanges of the other die member of said pair having extension portions of a length to span said parting line and engage in said recesses.
2. In apparatus for bending a metal workpiece

of the type having an intermediate web portion and longitudinal edge flanges, a die member having an intermediate plate portion and substantially parallel side flange portions, a second die member adapted to extend between said side flange portions for cooperation with the first die member in holding the web portion and edge flanges of said workpiece thereagainst and having a curved anvil portion, and a bending die member also having an intermediate plate portion and substantially parallel side flange portions and being rockable around said curved anvil portion for bending said web portion of the workpiece out of its own plane and around said anvil portion and simultaneously bending the edge flanges of the workpiece within their own planes, said bending die member having an initial position in which its side flange portions are substantially in alignment with the side flange portions of said first die member and in which adjacent edges of said first die member and bending die member are in substantially meeting engagement and define a parting line, said side flange portions of said first die member having recesses extending thereinto at one end thereof from said parting line and said side flange portions of said bending die member having end projections thereon of a length to span said parting line when said bending die member is in said initial position and adapted to move into and out of said recesses during rocking of said bending die member around said anvil portion.

3. In bending apparatus of the character described, an anvil die member engageable with one side of a metal workpiece having a web portion and a longitudinal edge flange, said anvil die member having a curved anvil portion and a substantially flat side face, a second die member engageable with the other side of said workpiece for clamping the same against said anvil die member and having a side flange overlapping said flat side face for holding said edge flange of the workpiece thereagainst, means supporting said anvil die member and said second die member so that one of these die members is movable relative to the other for clamping or releasing the workpiece, means for actuating said one die member, a bending die member rockable around said curved anvil portion for bending said web portion therearound and out of its own plane and simultaneously bending said edge flange within its own plane, and means for imparting such rocking movement to the bending die member, said bending die member also having a side flange overlapping said flat side face of the anvil die member and said second die member and said bending die member having cooperating edge

portions which define a common parting line when said bending die member is in its initial position and across which parting line said workpiece extends, the side flange of said second die member terminating short of said parting line and the side flange of said bending die member having an end extension of a length to span said parting line when said bending die member is in said initial position and which exerts an ironing action on said edge flange during rocking of said bending die member.

4. In a bending machine of the character described a frame, a pair of cooperating clamping die members adapted to receive therebetween a metal workpiece having a web portion and a continuous edge flange, one of said die members being movable for clamping the workpiece against the other die member and one of said die members having a curved anvil portion adapted for bending of said web portion therearound and a substantially flat side face adapted to be overlappingly engaged by said edge flange, a bending die having an initial position in which it cooperates with one of said clamping die members in defining a parting line and being rockable in one direction about said anvil portion for bending said web portion out of its own plane and around the latter and simultaneously bending said edge flange within its own plane, said bending die having a side flange overlapping said side face of the anvil die for holding said edge flange against the latter and said bending die being rockable in the other direction to return the same to said initial position, a carrier for said bending die, said carrier being mounted on said frame for swinging movement so as to cause said rocking of said bending die, and means for swinging said carrier, the side flange of said bending die having an extension portion of a length to span said parting line when the bending die is in said initial position and adapted to iron said edge flange against said side face during the return movement of the bending die.
